UNITED STATES PATENT OFFICE

TORD ERIK DANIEL BILDE, OF STOCKHOLM, SWEDEN, ASSIGNOR, BY MESNE ASSIGNMENTS, TO ELECTROLUX CORPORATION, A CORPORATION OF DELAWARE

VACUUM CLEANER

Application filed February 25, 1930, Serial No. 431,241, and in Germany March 5, 1929.

This invention relates to vacuum cleaners, and more particularly to a new and improved type of motor support for resiliently mounting a motor therein. The invention is particularly applicable to a vacuum cleaner having a horizontal casing in which the motor and fan are mounted as a unit and provides for preventing mechanical vibrations from being transmitted between the motor and the casing whereby a substantially vibrationless and noiseless operation is effected.

An object of the invention is to provide a resilient support for the motor unit of a vacuum cleaner. Other objects of the invention are: To provide an insulating support for the motor whereby the electrical circuit is insulated from the casing of the vacuum cleaner; to provide a resilient support at substantially the center of gravity of the motor unit whereby torsional forces are eliminated; to provide a support which affords a limited range of movement to the motor unit with respect to the stationary part of the vacuum cleaner, so that the unit is protected from shocks and jars and the vibrations of the motor are not imparted to the stationary part of the cleaner; to provide a free, floating, resilient support for the motor unit; and to provide a cheap, simple, convenient and efficient device of the type above indicated.

This invention also consists in certain new and original features of construction and combination of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which:

Fig. 1 is a side elevation of a vacuum cleaner unit partly broken away to show the motor unit and support; and

Fig. 2 is a section on the line 2—2 of Fig. 1.

In the following description and in the claims parts will be identified by specific

names for convenience, but they are intended to be as generic in their application to similar parts as the art will permit.

Referring to the drawings more in detail, one embodiment of the invention is shown as applied to a vacuum cleaner unit comprising a cylindrical barrel 10 having a ring 11 mounted at one end thereof and a ring 12 mounted near the other end thereof in the plane of the motor support, to be described. Bell 13, which is provided with a central aperture formed to receive coupling member 14, is seated on ring 11 and secured thereto by any convenient means. Coupling member 14 has a bore for receiving a flexible air hose or similar device. Cap 16, which is also provided with a central aperture for receiving coupling member 14, is telescoped over the end of barrel 10 and seated against ring 12 to which it is secured by any suitable means.

A flexible handle 17 is connected to barrel 10 and ring 12 by members 19 and 20 respectively. Said handle is preferably located at the center of gravity of the cleaner unit and facilitates transportation thereof. Runners 21 are mounted in lugs 22 and 23 formed on rings 11 and 12 respectively and support the unit on a surface, such as a floor. Shield 24 is mounted within barrel 10 and separates the dust bag compartment from the compartment containing the motor unit. Said shield is provided with a central aperture 25 for the admission of air to the fan which is covered by a screen 26 for preventing undesired particles of material from being drawn into said fan.

Motor 30, having a shaft 33, is mounted within housing 31. Fan 32 is carried on shaft 33 and is supported thereby. Motor 30, housing 31 and fan 32 constitute the motor unit, which may be assembled independently of the other parts of the vacuum cleaner and secured therein by a supporting mechanism to be described.

For supporting the motor unit within barrel 10 there is provided a ring 35 which is preferably formed of insulating material, such as rubber, phenol condensation product or similar substance. Said ring is mounted

within barrel 10 in the plane of ring 12 and is secured thereto by screws 36. Ring 35 is provided with pairs of recesses 37 which are inclined to the plane of said ring on opposite sides thereof.

Housing 31 of motor 30 is provided with lugs 38 which are cast integrally therein and have recesses 39 which are in alignment with recesses 37 when the housing is in operative position. Spiral springs 40 are seated in recesses 37 and 39 and support housing 31 and the motor unit. Said spiral springs are arranged in pairs and are oppositely inclined to the plane of ring 35. The entire supporting assembly including ring 35 and the cooperating springs are preferably mounted in a plane extending through the center of gravity of the motor unit whereby the unit is freely supported and torsional forces are eliminated.

The support is simple and cheap to manufacture and provides a convenient mounting for the motor which may be readily applied or dissembled. The entire motor unit including the motor and fan are resiliently mounted with respect to the casing of the vacuum cleaner unit whereby transmission of vibrations therebetween is prevented. This results in a substantially vibrationless and noiseless operation while the electrical insulation serves to isolate the current-carrying elements and eliminates the possibility of the operator receiving an accidental shock.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention. Furthermore, it will be understood that while one embodiment is illustrated, the invention is not to be limited except by the scope of the appended claims considered in the light of the prior art.

What I claim is:

1. In a vacuum cleaner having a cylindrical casing member, a motor, a housing therefor and means for mounting said housing in said casing member comprising a ring of insulating material secured to said casing member, and spiral springs interconnecting said ring with said housing.

2. In a vacuum cleaner having a cylindrical casing member, a motor, a housing therefor and means for mounting said housing in said casing member comprising a ring of insulating material secured to said casing member, and spiral springs interconnecting said ring with said housing, said ring and said housing having aligned recesses in which said springs are seated.

3. In a vacuum cleaner having a substan-

tially cylindrical casing member, a motor unit, a support therefor comprising a ring of insulating material secured to said casing member and spiral springs arranged in pairs oppositely inclined to the plane of said ring, 70 said pairs being spaced peripherally of said ring.

4. A vacuum cleaner comprising a cylindrical casing, a motor unit and means for mounting said motor unit coaxially within 75 said casing comprising springs arranged in pairs between said motor unit and said casing, said springs being oppositely inclined to a plane perpendicular to the axis of said casing.

5. A vacuum cleaner comprising a substantially cylindrical casing member, a motor, a housing for said motor, a ring of insulating material secured to said casing member, said housing and said ring formed with corresponding pairs of oppositely inclined recesses, and pairs of oppositely inclined springs retained in corresponding recesses 85 for supporting said motor in said casing.

6. In a vacuum cleaner, a horizontally supported cylindrical casing, a motor, and means for resiliently supporting said motor in said casing comprising spiral springs extending between said motor and said casing, said springs being peripherally spaced about said 95 motor and said casing and having their axes angularly disposed with respect to and being symmetrical with respect to a plane transverse to the axis of said casing.

7. In a vacuum cleaner having a cylindrical casing member, a motor, a housing therefor, and means for mounting said housing in said casing member comprising a ring of insulating material secured to said casing member, and spiral springs interconnecting said ring with said housing, said springs being peripherally spaced equidistantly about said ring and having their axes disposed angularly with respect to and being symmetrical with respect to a plane transverse to the axis of said casing member.

8. In a vacuum cleaner having a casing, means for supporting said casing in horizontal position above a horizontal surface, a motor, a housing therefor, and means for mounting said housing in said casing axially thereof comprising a ring of insulating material extending circumferentially of said casing, and spiral springs interconnecting said ring with said housing and disposed between 110 said ring and said housing.

In testimony whereof I have affixed my signature.

TORD ERIK DANIEL BILDE.
